UNITED STATES PATENT OFFICE

2,142,083

REFRIGERATOR

Clara E. Quinn, St. Petersburg, Fla.

Application November 27, 1937, Serial No. 176,777

12 Claims. (Cl. 62—49)

This invention relates to improvements in refrigerators, particularly refrigerators of the type employing water ice as the source of refrigeration.

An object of this invention is to employ a water 5 ice refrigerant in association with a heat absorption system exposed to the space to be refrigerated and thermo-dynamically connected with the primary refrigerant through the agency of a circulating secondary refrigerant.

10 A further object of this invention is to incorporate a combination of the above type in a construction whereby the space to be refrigerated may be maintained at relatively lower temperatures with water ice than is possible using water ice alone.

A further object of this invention is to incorporate in a construction of this nature arrangements whereby the ice water resulting from the melting of the ice may be drained from the refrigerator through a drainage system arranged centrally with respect to the space to be refrigerated, and so constructed as to expose the ice water to the circulating air within the space to humidify it and clean it by the absorption of odorous vapors.

25 A still further object is to provide in such a construction arrangements whereby the storage shelves in the refrigerated compartment are rotatably mounted around the central drainage system so that ready access to the contents of the refrigerated space may be had.

30 Other objects of this invention which are successfully secured will become apparent from the following detailed description of one physical construction embodying the above combination and principles.

This invention resides substantially in the combination, construction, arrangement and relative location of parts as will be fully described.

In the accompanying drawings,

40 Figure 1 is a vertical, central, cross-sectional view through a construction embodying the invention herein;

Fig. 2 is a side elevational view of one of the heat absorbing fins;

45 Fig. 3 is a vertical, cross-sectional view therethrough;

Fig. 4 is an enlarged vertical, cross-sectional view through a portion of the mechanism showing the details thereof;

50 Fig. 5 is a cross-sectional view taken on the line 5—5 of Figure 1;

Fig. 6 is a central, vertical, cross-sectional view through one of the shelf supporting rings; and

55 Fig. 7 is a top plan view of the complete refrigerator.

The structure is illustrated in the drawings as comprising a heat insulating casing 1 of generally circular cross-section enclosed in a suitable protective and decorative metal casing 2. This casing is extended below the insulated casing so as to

form a bottom wall 6 for the insulated casing and a chamber A in which the ice water pan 7 may be placed through an opening closed by a suitable door 5. The upper part of the casing comprised of the insulating lining 1 and metal covering 2 is provided with two openings which are closed by means of removable closure members or doors 3 and 4.

Disposed within the space defined by the upper portion of the casing so as to provide a substantially horizontal partition, is a container 8 which is substantially a double walled slightly conical member circular in outline and fitting snugly within the insulating casing to divide the space therein into chambers B and C. The chamber 15 B is adapted to receive, through the opening closed by the door 3, any suitable solid refrigerant such as water ice, as indicated at 9. The block of ice rests upon the upper wall of the container 8.

20 Secured to the bottom wall of container 8 in heat conducting relation by soldering, welding, or incorporation directly therein, as an integral part are a plurality of radially extending, circumferentially spaced metal fins 10 which have secured to their bottom edges gutters 11 which incline downwardly towards a common point, as is clear from Figure 1. Extending through the center of the container 8 in a vertical direction and forming a liquid-tight seal therewith is an ice water 30 drain tube or spout 12.

25 Telescoped with the end of the spout 12 is a vertical drain tube 13 which has mounted therearound on open top container or pan 14. The tube 13 has a series of small holes 15 therethrough on a level above the bottom of the pan 14. The discharge ends of the gutters 11 are arranged to discharge into the pan 14. Thus 35 the condensate which collects on the cold fins 10 is drained by the gutters 11 into the pan 14 where it accumulates until it reaches a level so as to discharge through the openings 15 into tube 13 to join the ice water coming down the tube from the melting ice.

Secured to the lower end of the tube 13 is a container 16 which is provided on a radially inwardly extending flange at its upper edge with a series of bearing balls 19 to form a circular track. At 18 is a circular shelf provided with a groove to ride on the circular ball track and provided with a circular 50 central opening so that the water in the pan 16 will be exposed to the air in the compartment C.

The outer peripheral edge of the disc 18 is supported on a ball bearing race 20. The tube 13 is provided with a series of openings 17 through the wall thereof above the level of the bottom of pan 16.

55 Telescoped for a short distance with the lower end of tube 13 is a tube 21, the lower end of which is attached to another open top container 60

or pan 22 supporting the circular shelf 23 by the ball bearing 24 and the ball bearing ring 25. The details of the construction of pan 22, which are the same as the construction of pans 5 16 and 28 are shown more clearly in Fig. 4. The tube 21 is shown slightly enlarged in diameter at its lower end as shown at 21^a so as to receive and telescope with the upper end of the next tube 27. The upper ends of the tubes 10 21 and 27 are conical in shape, as shown at 27^a and the portion 21^a of the tube 20 is provided with a series of openings 26 on the level with the upper end of the tube 27. These openings correspond to the openings 17 and 37 in the 15 other tubes. As was the case of all the shelves, the shelf 23 is provided with a circular track 23^a to engage the ball race 24.

These details are further illustrated in connection with the shelf 18 in Fig. 5, wherein it 20 is provided with a circular groove forming a ball race at 18^a. All the shelves, as indicated in Fig. 5 in connection with the shelf 18, are provided with a similar circular race track 18^b, near their periphery to engage the ball bearing race on 25 the ring 20. The construction of the ring 20 which is similar to the rings 25, 30 and 35 is illustrated in Fig. 6. It is a ring of circular form having an inwardly projecting, radially extending flange in which are mounted, in any 30 suitable manner a series of bearing balls 20^a. They are arranged to engage with the circular track or groove 18^b. The result is that each shelf is supported near its center on ball races mounted in the flanges of the pans and at its 35 outer periphery on ball races mounted in the rings secured to the inner wall of the container. It is apparent as a matter of convenience that the rings 20, 25, 30 and 35 be interrupted by the openings closed by the door 3, so as not to obstruct it. Thus the rings may terminate at the 40 sides of the opening, or have segmental portions mounted on the door of the opening so as to be moved under and from under the adjacent edge of the shelves when the door opens. The tube 45 27 has secured to its lower end an open pan 28 having a ball race 31 engaging the shelf 27, which is supported at its outer edge by the ball bearing ring 30. At 32 is a final tube which passes through an opening in the bottom wall 50 of the container with which it has a sliding fit and is provided with a pan 33. This pan has the ball race 36 for supporting the center of the shelf 34, which is in turn supported at its outer periphery by the ball ring 35.

The upper ends of the tubes 21, 27 and 32, 55 as explained above, are conical in shape and the plane of their upper ends lie in the plane of the openings 17, 26 and 37, respectively. By this construction the water running down the tube 13 will catch in the circular space around the conical end of the tube 21 and flow through 60 the openings 17 filling the pan 16 to the level of the top end of the tube 21. The excess then runs down this tube to fill pan 22 in a similar 65 manner, after which the excess flows down pan 28 and from there discharges through the tube 32 into the pan 7. It will be noted that pan 33 does not serve any other function than as a bearing support for the center of disc 34. It 70 is not intended to receive any of the ice water.

It is of course apparent that some means should be provided to determine the amount of telescoping of the sections of the drain tube so as to properly lock the upper end of each section with the apertures through the wall of the 75

associated section and to insure that all the parts will be in their proper position. For this purpose the upper end of each drain tube may be of less diameter than the remainder thereof to form a shoulder on which the associated end 5 of the drain tube rests. However, an equally effective expedient which is structurally simpler consists in applying an annular ring around each section adjacent its conical end and spaced therefrom the necessary distance, as indicated 10 at 27^b. It is of course apparent that this ring may be formed by rolling an annular bead into the tube section.

By means of this construction it will be seen that the entire shelf and drain structure may be 15 easily disassembled in order to clean them. Thus by raising tube 13 slightly further, telescoping it with tube 12, it becomes free of the end of tube 21 and may then be removed. To facilitate this the tube 12 may have a loose fit with the 20 upper end of tube 13. If preferred, however, the tube 13 may simply be raised up as far as it will go, leaving space to raise tube 21, so as to free it from tube 27 when it may be removed. Tube 13 may then be dropped to remove it. In this 25 way the structure may be entirely disassembled. It will be noted that in raising each of the tubes the associated shelf and pan will be raised with it. The pans are secured to the tubes but the shelves may be lifted off the tubes to facilitate 30 cleaning, with the exception of shelf 18 which is between the pans 14 and 16.

Although the operation of the device will be apparent from the above description, it may be noted that the warm air will circulate upwardly 35 and over the fins 10, readily giving up its heat to them, and when chilled will circulate downwardly into the space to discharge additional heat. To facilitate this circulation a number of expedients may be followed to permit the passage 40 of air through or around the shelves. For example, they may be, as is common, of a reticulated or open construction. Thus all the shelves as illustrated for shelf 18 at 18^c may be provided with a series of apertures or they may be made 45 up of strips or wires so as to permit free circulation of air in the container. The open pans 14, 16, 22 and 28 expose the circulating air to the evaporating ice water serving to properly humidify the air while the remaining bodies of 50 water tend to absorb the odorous vapors, thereby purifying and cleansing the air. The construction permits of these features by reason of the center drain which facilitates the use of shelves which may be revolved so that they may be 55 easily loaded and unloaded, thus insuring complete use of the space.

Those skilled in the art will readily appreciate that the various features of this invention may be varied without departure from the novel scope 60 of the subject matter herein. I do not, therefore, desire to be strictly limited to the disclosure as given for purposes of illustration, but rather to the scope of the claims granted me.

What I seek to secure by United States Letters 65 Patent is:

1. A refrigerator including an insulating casing having a generally horizontal partition wall forming a closed container having a secondary refrigerant therein, said wall dividing the casing 70 into two compartments the upper of which is adapted to receive a solid refrigerant which rests on said wall, a plurality of rotatably mounted shelves supported in said lower compartment, and a vertical sectionalized drain tube for said 75

- wall extending centrally of the casing and passing through said shelves.
2. A refrigerator including an insulating casing having a generally horizontal partition wall forming a closed container having a secondary refrigerant therein and a drain spout, said wall dividing the casing into two compartments the upper of which is adapted to receive a solid refrigerant which rests on said wall, a plurality of shelves supported in said lower compartment, and a vertical sectionalized drain tube detachably connected to said spout and extending centrally of said shelves, there being one section for each shelf and removable therewith.
- 15 3. In a refrigerator the combination including an insulating casing, a hollow partition wall dividing the casing into two compartments, said hollow partition wall adapted to contain a secondary refrigerant, a center drain spout for said wall, a plurality of shelves supported in the lower compartment, and a sectionalized drain tube detachably connected to said spout, said sectionalized drain tube passing centrally through said shelves.
- 25 4. In a refrigerator as described the combination including an insulated casing circular in cross section, a refrigerant supporting wall dividing said casing into an upper and a lower compartment, a central drain spout for said wall, a plurality of rotatable circular shelves in said lower compartment, and a sectionalized drain tube detachably connected to said spout, each shelf having a section of said tube associated and removable therewith.
- 35 5. In a refrigerator as described the combination including an insulated casing circular in cross section, a refrigerant supporting wall dividing said casing into an upper and a lower compartment, a central drain spout for said wall, a plurality of circular shelves in said lower compartment, means for rotatably supporting said shelves, a sectionalized drain tube detachably connected to said spout, each shelf having a section of said tube associated and removable therewith, and a plurality of heat absorbing fins connected to said wall and exposed to the air in said lower compartment.
- 45 6. A refrigerator as described including an insulating casing, a heat conducting wall mounted in said casing and dividing it into upper and lower compartments, a drain spout for said wall, a plurality of shelves supported in said lower compartment, a sectionalized drain tube detachably connected to said spout, and an open container supported on the lower end of each section of the drain tube, said drain tube having apertures through the wall thereof above the bottom of the associated container, the upper end of each tube section being conical and disposed at the level of said opening.
- 55 7. In a refrigerator the combination including an insulating casing, a heat conducting wall dividing the casing into upper and lower compartments, a central drain spout for said wall, a plurality of shelves supported in said lower compartment, a sectionalized drain tube detachably connected to said spout, a plurality of heat conducting fins secured to said wall and exposed in the lower compartment, the plurality of gutters secured thereto and inclined towards a common
- point, and an open container secured to said drain tube and positioned to receive moisture from said gutters, said drain tube having apertures therethrough above the level of the bottom of said container.
- 5 8. In a refrigerator of the type described the combination including a heat insulating casing circular in cross section, a heat conducting wall dividing said casing into two compartments, a central drain spout for said wall, a plurality of 10 shelves in the lower compartment, a sectionalized drain tube detachably connected to said spout, and means for rotatably supporting said shelves including members engaging it at its outer periphery and near the center concentrically with 15 said drain tube.
9. In a refrigerator of the type described the combination including a heat insulating casing circular in cross section, a heat conducting wall dividing said casing into two compartments, a 20 central drain spout for said wall, a plurality of shelves in the lower compartment, a sectionalized drain tube detachably connected to said spout, means for rotatably supporting said shelves including members engaging it at its outer periphery and near the center concentrically with 25 said drain tube, and a plurality of heat conducting fins depending from said wall so as to be exposed to the circulating air in the lower compartment.
10. In a refrigerator construction the combination including a sectionalized drain tube comprising a plurality of partially telescoped longitudinally aligned sections, an open container secured to the lower end of each section and surrounding it, each section having apertures in the wall 30 thereof above the bottom of said container, and the telescoping ends of the next section being of less diameter to a portion thereof than the section with which it is telescoped, and its upper end being on the level with said apertures.
- 35 11. In a refrigerator of the type described the combination including an insulating casing, a shallow closed metal container dividing the casing into an upper and lower compartment, said container being intended to hold a secondary refrigerant, the upper wall of the container being intended to support a body of water ice, a central drain spout for the upper wall of the container, a sectionalized drain tube detachably connected to 40 said spout comprising a plurality of sections respectively telescoped at their ends, a plurality of shelves surrounding said drain tube, and means for supporting said shelves.
- 45 12. In a refrigerator of the type described the combination including an insulating casing, a shallow closed metal container dividing the casing into an upper and lower compartment, said container being intended to hold a secondary refrigerant, the upper wall of the container being intended to support a body of water ice, a central drain spout for the upper wall of the container, a sectionalized drain tube detachably connected to 55 said spout comprising a plurality of sections respectively telescoped at their ends, a plurality of shelves surrounding said drain tube, and means for supporting said shelves at the periphery and near the center, the means at the center including open containers communicating with 60 said drain tube.
- 65 CLARA E. QUINN. 70
